UNITED STATES PATENT OFFICE.

WILLIAM MACDONALD AND HUGH MACDONALD, OF INVERNESS, SCOTLAND.

HAIR WAVER.

Application filed February 14, 1924. Serial No. 692,828.

This invention relates to an appliance or apparatus for use in the waving of hair by the method known as permanent hair waving, of the type in connection with which steam is adapted to be brought into contact with the hair wound upon a tubular or rod-like element (which may be conveniently referred to hereinafter as "a hair waving bobbin") so as to treat the hair with moist or humid heat.

The object of the invention is to provide an appliance whereby the steam from an external source away from the head of the subject may be supplied around the hair waving device so that the latter is enclosed or immersed in an atmosphere of steam and the hair subjected to the contact of a constant stream of steam, thus abolishing the use of local electrical heaters commonly employed and securing an abundant supply of steam, heat and moisture for the hair.

A further object of the invention is to provide an appliance for enclosing the hair waving device into which the hair wound or coiled upon a hair waving device may be introduced with facility.

Various features of the invention will be hereinafter described and pointed out in the claims.

In the accompanying drawings:—

Figure 1 is a longitudinal section of a jacket or tubular appliance according to one form of the invention showing a hair waving bobbin of known type located therein for the treatment of the hair;

Figure 2 is a sectional elevation of a known type of hair waving bobbin appropriate for use in connection with the invention;

Figure 3 is a central longitudinal section of a modified form of jacket appliance for providing an atmosphere of steam round the hair to be treated;

Figure 4 is a cross-sectional view taken on the lines A—A of Figure 3;

Figure 5 is a perspective view of a detachable or removable part of the jacket shown in Figures 3 and 4;

Figure 6 is an outside view of a tube of the kind shown in Figure 1 but of shorter length and provided with a lateral egress for the portion of a tress of hair which does not require treatment.

In carrying the invention into effect according to one form, the jacket for the hair waving device is constituted by a tube 1 of

suitable dimensions to include or enclose the hair waving device 2. Towards one end of the tube 1, namely toward that end to be adjacent the roots of the hair, an annular channel member 1^a is provided with a nipple 3 to which may be attached a conduit 4 for conveying steam to the space within the annular member from a suitable external source. Instead of making the channel member 1^a annular so as to surround the periphery of the tube 1 it may be localized to the position occupied by the nipple 3 or may extend over an appropriate segment of the tube. The wall of the tube 1 included by the member 1^a is provided with a series of orifices or perforations 5 (localized near a transverse plane towards one end of the tube) through which the steam can escape from the space within the conduit member 1^a and is introduced laterally into the interior of the tube 1 or transversely to the axis thereof so that it may circulate around the hair on the bobbin 2, that is to say, so that the hair is immersed in and in direct contact with, a moving atmosphere of steam.

The end of the jacket remote from the head of the subject may be partially closed by an orificed detachable rubber cap 6. The orifice may serve for the escape of steam and the part of the tress which is not to be treated may also be passed through this orifice. If a cap is fitted without an orifice some other vent should be provided for the escape of the steam.

The sleeve bearing cap 7 should fit tightly over the tress of hair at the point where it enters the tube and is intended to prevent the escape of steam from the tube toward the head of the subject.

Outside the rubber sleeve bearing cap 7 a rubber cup 7^a may be provided which also is adapted to fit over the tress of hair where it enters the jacket. This cup-shaped member 7^a is intended for the purpose of catching any condensation water which may leak past the cap 7. Both the apertures, for the hair to pass through, in the sleeve bearing cap 7 and cup 7^a may be eccentrically arranged (see Figure 1).

Any appropriate hair waving bobbin may be employed; for example such may comprise an outer tube 8 (see Figure 2) mounted upon a slotted ferrule 9, the slot being provided for the purpose of facilitating the securing or tying of the tress of hair to the ferrule.

In rear of the ferrule a rod 10 is provided which has on its outer end a manipulating piece 11, the arrangement being such that by operating the manipulating piece 11 the tube and ferrule may be given relative rotary motion.

12 indicates a spring-locking device adapted to engage with one or other of the holes 13 in the tube 8 in order to lock the ferrule with respect to the tube in any adjusted position after the coil has been tightened.

In carrying the invention into effect according to another mode (see Figures 3, 4 and 5) the single wall jacket has a portion thereof removable. According to the form illustrated in the drawings the jacket is formed by a three-quarter tubular piece 14 adjacent the longitudinal edges of which 20 guideways 15 are provided for the reception of an arc or segment-shaped strip or quarter-tube piece 16, so that the latter may be slid into the guideway longitudinally to convert the three-quarter tube into a complete 25 tube or jacket. The piece 16 should be of substantially the same length as the three-quarter tube 14. Either the three-quarter tube 14 or the segmental piece 16 is provided with a steam conduit for conveying 30 steam from a suitable source and directing it laterally into the space enclosed by the jacket or composite tube.

In the drawings the segmental strip or part 35 16 is illustrated as provided with a conduit 17 which communicates with the interior of the jacket through perforations 18. It is preferred that these perforations should be inclined or should occupy approximately a tangential position (see Figure 4) with respect to the jacket so that steam issuing 40 from the conduit 17 enters the jacket and flows round the walls with a swirling or helical action. These perforations it is preferred to confine to the portion of the jacket 45 adapted to lie adjacent the head of the patient so that the portion of the hair nearest its roots is treated to the hottest of the steam issuing from the conduit. The conduit 17 may be bent upwardly as at 19, for convenience in attaching the conduit to a steam 50 conveying tube 20, which communicates with a suitable boiler.

The outer end of the composite or divisible jacket may be partially closed by a rubber cap or the like 21 which has a central opening through which the steam may escape after having treated the hair.

The inner end of the jacket may be provided with a cap 7 and cup 7^a as described 60 in connection with Figure 1 or the holes for the passage of the hair may be central as illustrated in Figure 3.

Assuming that it is desired to treat a tress of hair wound upon a hair waving bobbin such as shown in Figures 3, 4 and 5, the hair

after having been drawn through the cap 7 and the cup member 7^a is wound upon the hair waving bobbin 2 according to ordinary practice. The bobbin with the hair wound thereon is then inserted through the opening 70 in the three-quarter tube bounded by the guides 15, the segmental piece 16 having been removed. When the hair waving appliance is in position, the rubber caps 21 and 75 7 are fitted over the ends of the tubes.

For convenience in fitting the cap 7 its lip may be reversed so as to lie over toward the cup 7^a and then bent back again in applying it to the tube.

In order to position the bobbin 2 within the jacket (whether of the form shown in Figure 1 or Figure 3) a resilient tripartite spider 24 or other support may be permanently fixed or temporarily slipped upon the device 2, so that the legs of the spider lightly engage the interior walls of the jacket. Where a spider such as 24 is used a cap and cup member centrally perforated should be preferably employed.

We wish it to be understood that our invention is not confined to the precise details and arrangement of parts illustrated and described as such may be modified according to requirements or the circumstances attendant upon the application of the invention.

According to a modification of the form of device shown in Figure 1, a shorter tube 1 (see Figure 6) may be employed, which is provided with an elongated cap 6 having a lateral slot 6^a to permit that portion of the hair which it is not desired to treat to be carried out of the jacket with facility. Sometimes it is desired only to treat a small portion of a tress of hair quite close to the roots. In these circumstances a considerable portion of the tress is left unwound and presents a problem as to what is to be done with it and how to get it out of the way. The provision of the slot 6^a affords a ready means of disposing of such a portion of hair as referred to as such can be accommodated in the slot without the necessity of having to thread it through an aperture.

This form of the appliance may be looked upon as providing a tube which is divisible transversely and when the two parts, i. e. the short tube 1 and the elongated cap 6, are fitted together an enclosing composite tube or jacket is formed for a hair waving bobbin.

Having now described our invention, what we claim as new and desire to secure by Letters Patent is:—

1. An appliance of the type described comprising a jacket into which a hair waving bobbin may be introduced, means for conveying steam to the jacket from a source away from the head of the subject, and means adapted to admit steam into the interior space surrounded by the jacket later- 125 130

ally thereof and transversely to the axis thereof, so that the hair under treatment is immersed in and in direct contact with, a moving atmosphere of steam whereby the hair is treated by steam initially applied externally of the coil of hair.

2. An appliance of the type described comprising a tubular member having laterally arranged perforations and adapted to constitute a jacket into which a hair waving bobbin may be introduced and means adapted to convey steam from a source away from the head of the subject to outside of the wall of the tubular member and to the perforations so that steam is introduced laterally into the interior space surrounded by the jacket and transversely to the axis thereof, whereby the hair under treatment is immersed in and in direct contact with a moving atmosphere of steam and the hair is treated by steam initially applied externally of the coil of hair.

3. An appliance having the features claimed in claim 1 and including resilient means (such as, for example, the cap 7) detachably connected to the jacket and adapted to close one end thereof upon the tress of hair wound on the hair waving bobbin in a substantially steam-tight manner, said means having an orifice through which the hair is drawn.

4. An appliance of the type described comprising a tubular member having laterally arranged perforations and adapted to constitute a jacket into which a hair waving bobbin may be introduced, means adapted to convey steam from a source away from the head of the subject to outside of the wall of the tubular member and to the perforations, so that steam is introduced laterally into the interior space surrounded by the jacket and transversely to the axis thereof, whereby the hair under treatment is immersed in and in direct contact with a moving atmosphere of steam and the hair is treated by steam initially applied externally of the coil of hair, and resilient means (such as, for example, the cap 7) detachably connected to the jacket and adapted to close one end thereof upon the tress of hair wound on the hair waving bobbin in a substantially steam tight manner, said means having an orifice through which the hair is drawn.

5. An appliance of the type described comprising a tubular member having laterally arranged perforations and adapted to constitute a jacket into which a hair waving bobbin may be introduced, means adapted to convey steam from a source away from the head of the subject to outside of the wall of the tubular member and to the perforations, so that steam is introduced laterally into the interior space surrounded by the jacket and transversely to

the axis thereof, whereby the hair under treatment is immersed in and in direct contact with a moving atmosphere of steam and the hair is treated by steam initially applied externally of the coil of hair, resilient means (such as, for example, the cap 7) detachably connected to the jacket and adapted to close one end thereof upon the tress of hair wound on the hair waving bobbin in a substantially steam tight manner, and an orifice and detachable cap (such, for example, as the cap 6) for the other end of the jacket, the arrangement being such that steam may escape and the part of the tress of hair which is not to be treated may be passed out of the jacket through the orifice in the cap.

6. An appliance of the type described comprising a tubular member adapted to constitute a jacket into which a hair waving bobbin may be introduced and having laterally arranged perforations localized near a plane transverse to the axis of the tubular member and means adapted to convey steam from a source away from the head of the subject to a conduit upon the outer side of the wall of the tubular member and including the said perforations so that the steam is introduced laterally through the perforations into the interior space surrounded by the jacket and transversely to the axis thereof whereby the hair under treatment is immersed in and in direct contact with a moving atmosphere of steam and the hair is treated by steam initially applied externally of the coil of hair.

7. An appliance of the type described comprising a tubular member adapted to constitute a jacket into which a hair waving bobbin may be introduced and having laterally arranged perforations localized near a plane transverse to the axis of the tubular member, means adapted to convey steam from a source away from the head of the subject to a conduit upon the outer side of the wall of the tubular member and including the said perforations so that the steam is introduced laterally through the perforations into the interior space surrounded by the jacket and transversely to the axis thereof whereby the hair under treatment is immersed in and in direct contact with a moving atmosphere of steam and the hair is treated by steam initially applied externally of the coil of hair, and resilient means (such, for example, the cap 7) detachably connected to the jacket and adapted to close one end thereof upon the tress of hair wound upon the hair waving bobbin in a more or less steam tight manner, said means having an orifice through which the hair is drawn.

8. An appliance of the type described comprising a tubular member having perforations therein and adapted to constitute a jacket into which a hair waving bobbin may

be introduced, means adapted to convey steam from a source away from the head of the subject to the outside of the wall of the tubular member so that the steam may pass into the interior of the jacket to surround the hair under treatment with a moving atmosphere of steam, a cap having a hole for accommodating a tress of hair adapted to fit over one end of the tubular member, a rubber cup member adapted to fit outside the rubber cap to catch any condensation water which may leak through said cap and a second cap having a hole for the escape of steam from the interior of the tubular member adapted to fit over the other end of the latter.

9. An appliance of the type described consisting of a tubular member comprising two parts which are separable one from the other and which when united are adapted to constitute a complete jacket for the reception of a hair waving bobbin, one part having perforations arranged laterally therein and a conduit to which steam is supplied and which is in communication with said perforations so that steam is introduced into the interior space surrounded by the jacket in a direction transverse to the axis thereof.

10. An appliance of the type described consisting of a tubular member comprising two parts which are separable one from the other by a sliding movement longitudinally of the jacket and which when united are

adapted to constitute a complete jacket for the reception of a hair waving bobbin, one part having perforations arranged laterally therein and a conduit to which steam is supplied and which is in communication with said perforations so that steam is introduced into the interior space surrounded by the jacket in a direction transverse to the axis thereof.

11. An appliance as claimed in claim 10 wherein one part is provided with a longitudinally extending slot adapted to provide an opening through which the part of the tress of hair not undergoing treatment may pass.

12. An appliance of the type described consisting of a jacket for the reception of a hair-waving bobbin which is divisible longitudinally into two parts, one being substantially a three-quarter tube and the other substantially a quarter segment, and means providing for sliding the two parts longitudinally and relatively to one another, one of the parts being provided with a conduit for supplying steam from a source away from the head of the subject and having perforations to admit steam into the interior of the jacket to surround the hair-waving device therein with an atmosphere of steam.

In testimony whereof we have signed our names to this specification.

WILLIAM MACDONALD.
HUGH MACDONALD.
